DESIGN FOR A COMBINED ASHTRAY AND CIGARETTE CONTAINER

Maxon Lester Graham, Seattle, Wash.

Application November 3, 1936, Serial No. 65,684

Term of patent 3½ years

To all whom it may concern:

Be it known that I, Maxon Lester Graham, a citizen of the United States, residing at Seattle, in the county of King and State of Washington, have invented a new, original, and ornamental Design for a Combined Ashtray and Cigarette Container, of which the following is a specification, reference being had to the accompanying drawing, forming a part thereof.

Figure 1 is a front elevation of a combined ash-

tray and cigarette container showing my new design.

Figure 2 is a side elevation.

Figure 3 is a rear elevation.

Figure 4 is a top plan view.

I claim:

The ornamental design for a combined ashtray and cigarette container, as shown.

MAXON LESTER GRAHAM.
